SUSPENSION INSULATOR

John J. Taylor, Wadsworth, and Floyd G. Bovard, Akron, Ohio, assignors to The Ohio Brass Company, Mansfield, Ohio, a corporation of New Jersey

Application April 20, 1935, Serial No. 17,440

10 Claims. (Cl. 173—318)

This invention relates to suspension insulators for electrical transmission lines, and particularly for insulators intended to be used in regions where the atmosphere is apt to be contaminated with fog, dust, smoke or other impurities.

One object of the invention is to provide an insulator in which the surfaces subjected to highest stresses are protected from contamination.

Another object of the invention is to provide an insulator in which the metallic fittings and the dielectric surfaces adjacent these fittings are completely enclosed so as to prevent contamination of the surfaces adjacent the fittings.

A further object of the invention is to provide an insulator string in which the adjacent units are provided with overlapping flanges forming an outer armor of dielectric material constituting the entire surface of said string.

Another object of the invention is to provide a string made up of insulator units articulated to one another so as to permit flexing of the string, adjacent units in the string having overlapping flanges affording sufficient clearance to permit flexing and yet providing a shell presenting an outer dielectric surface throughout the entire length of the string.

A further object of the invention is to provide an insulator string having overlapping flanges arranged to provide a maximum amount of protected leakage surface with a minimum length of string.

A further object of the invention is to provide a device of the class named which shall be of improved construction and operation.

Other objects and advantages will appear from the following description.

The invention is exemplified by the combination and arrangement of parts shown in the accompanying drawings and described in the following specification, and it is more particularly pointed out in the appended claims.

In the drawings:

Fig. 1 is an elevation with parts in section showing one embodiment of the present invention.

Figs. 2 and 3 are views similar to Fig. 1 showing modified forms of the invention.

Referring first to Fig. 1 of the drawings, the numeral 10 designates the dielectric member of an insulator unit which may be made of porcelain or other dielectric material. The member 10 is provided with a boss 11 having a recess opening at the upper side of the insulator, in which recess a pin 12 is secured by cement or other suitable means. The cap 13 surrounds the boss 11 and

is secured thereto by cement 14. The porcelain member 10 has a radially projecting flange 15 having a downwardly projecting portion provided with skirts 16 and 17. The flange 15 also has upwardly projecting baffles 18 and 19 which overlap the downwardly projecting skirts 16 and 17 of the next adjacent unit in the string and which are staggered relative to the skirts 16 and 17. Since the cap 13 is of much greater diameter than the pin 12, the flanges 16 and 17 surrounding the cap are likewise of greater diameter than the corresponding flanges 18 and 19 surrounding the pin and so, due to the relative position of the cap and pin, overhang the flanges 18 and 19 and protect the recesses within these flanges from rain and snow. If the cap were placed at the top of the insulator, as has heretofore been the usual custom, the flanges about the pin would have to extend beyond those about the cap to give the same protection, thus requiring flanges of excessive diameter. By inverting the units as shown in the drawings, the downwardly projecting flanges 16 and 17, which must be of sufficient diameter anyway to surround the cap, easily overlap the upwardly projecting flanges 18 and 19 surrounding the pin, without the necessity of using flanges of excessive diameter. The pin 12 has a ball and socket connection with the cap 13 of the next adjacent unit in the string so as to permit bending of the string.

In order to facilitate assembly of the units, the pin 12 is formed of upper and lower sections connected by a thread 20. The ball on the upper end of the pin 20 is provided with a web 21 which fits in the slotted opening 22 of the socket on the cap 13 to prevent rotation of the pin relative to the socket. This facilitates threading of the parts of the pin together during assembly. The upper end of the pin is first inserted in the socket and is locked in place by a cotter 23 in a manner well known in the art. The lower unit is then threaded onto the upper portion of the pin. The upwardly projecting baffles 18 and 19 may be omitted from the uppermost unit of the string and the space about the pin 12 may be filled by a weather proofing compound 25. Any number of units similar to the unit 10 may be connected in the string. The lowermost unit will support the usual conductor clamp 26. The fitting for the clamp may be provided with a sheet metal bowl shaped baffle 27, the periphery of which projects between the skirts 16 and 17 to insure protection of the dielectric surface about the cap 13.

By placing the cap on the lower side of the dielectric member rather than on the upper side,

as is usual with suspension insulators, a more effective disposition of the flanges is secured. It is necessary for the downwardly extending skirts to project radially beyond the upwardly extending skirts in order to shed the rain; and since the pin is the smaller one of the two metal fittings, it is desirable to place this at the top of the insulator so that the upwardly projecting flanges may be brought inwardly as near the axis 10 of the string as possible, thus permitting the downwardly extending flanges to project radially beyond those extending upwardly. The flanges which overlap the cap must necessarily be spaced outwardly beyond the periphery of the cap, and 15 by placing the cap on the lower side of the dielectric member, advantage is taken of this greater diameter to locate the overlapping flanges in the proper radial relation to one another so as to shed rain or snow. It will be noted that 20 the string length is no greater than that of the usual suspension insulator string of the same number of units since the flange extending backwardly over the cap occupies the same linear space as the boss on which the cap is attached. 25 Each unit is prevented from rotation relative to the next adjacent unit by the web 21 on the pin, and since the end units are both held from rotation, the pin sections will be prevented from unscrewing. A spacer washer 24 may be provided for regulating the spacing between the 30 units.

In the form of the invention shown in Fig. 2, the integral dielectric flange 19 is omitted and instead a metal flange or ring 27 is employed. 35 This flange is provided with a bead 28 that fits in a slight depression in the porcelain member 10 to hold it in place. The flange 28 is slightly corrugated or slotted to provide sufficient resiliency to permit the bead to pass downwardly out of 40 its groove so that the entire flange 27 may be slid downwardly to provide sufficient clearance to permit assembly of the insulator parts without the necessity of providing a separable pin. The pin 30 in this case is made of one piece and 45 the insulator units may be assembled in the usual way by first sliding the metal flange 27 downwardly so as to permit of sufficient angular tilting of the parts to insert the ball 31 in the socket 32. The uppermost unit in the string in this 50 case is provided with an upwardly extending baffle 33 and the supporting fitting 34 carries a canopy 35 which overlaps the baffle 33 and prevents precipitation from entering the space inside the baffle 33. The metal flange 27 is provided with 55 a drain opening 36 covered by an outwardly spaced baffle plate 37 to prevent currents of air from passing through the drain opening.

In the form of the invention shown in Fig. 3, an upwardly projecting movable flange 40 is provided similar to the flanges 27 in Fig. 2, and also a downwardly projecting flange 39 which overlaps the flange 40. This arrangement not only permits easy assembly of the parts but also by sliding the flange 40 downwardly and the flange 39 upwardly, access may be had to the space about the metal fittings for cleaning or other purposes.

It will be noted that in each form of the invention shown, an extended leakage surface adjacent the metal fitting is protected so as to maintain a dry surface at this position at all times. 70 This is the position of greatest electrical stress and the point where corona or sparking is most apt to occur if the surface should become contaminated. The entire metallic connection is 75 enclosed in the space surrounded by the overlap-

ping baffles which provide a labyrinthine passage between the enclosed space and the outer atmosphere, thus preventing air currents and contamination carried thereby from entering this space.

We claim:

1. An insulator string comprising a plurality of units each having flanges thereon and having fittings connecting said units together in the strings, the flanges of adjacent units surrounding the fittings connecting said units and being arranged in overlapping relation, one of said flanges being readily movable relative to its unit even after the unit and flange are completely assembled to facilitate assembly of the units in the string. 10

2. An insulator formed of a plurality of units in a string, means for separably connecting said units together, adjacent units having flanges thereon overlapping each other and enclosing said connecting means, two of said overlapping flanges, one on each unit, each being readily movable relative to the unit with which it is connected even after completely assembled with said unit to permit access to the means for connecting said units. 20

3. An insulator string formed of a plurality of units, each comprising a dielectric member and metal fittings for connecting said member with adjacent units in the string, the units in said string having baffles thereon extending longitudinally of said string, a baffle on one unit overlapping an oppositely extending baffle on an adjacent unit and forming an enclosed housing connected to the outer atmosphere by a labyrinthine passage, one of said baffles being movable relative to the unit on which it is mounted to permit more ready access to the interior of said housing. 30

4. An insulator string formed of a plurality of units, each unit comprising a dielectric member and metal fittings for connecting adjacent units in said string, one of said units having a separately formed metallic baffle mounted thereon and arranged to telescope relative to said unit and spaced away from said fittings by the dielectric member of said unit and overlapping a cooperating flange on an adjacent unit to provide an enclosed space about said fittings and form a labyrinthine passage between said space and the outer atmosphere. 45

5. An insulator string formed of a plurality of units, each unit comprising a dielectric member and metal fittings for connection with adjacent units in the string, adjacent units having overlapping flanges forming an enclosed chamber and providing a labyrinthine passage connecting said chamber with the outer atmosphere, certain of said flanges being formed of metal and being movably supported on said dielectric members in spaced relation to said metal fittings, said metal flanges being movable relative to said dielectric members to open said labyrinthine passage. 55

6. An insulator string formed of a plurality of units connected together by ball and socket joints, adjacent units in said string having oppositely extending flanges thereon arranged in overlapping relation to enclose the joint between said units, one of said flanges being movable relative to its unit to facilitate assembly of the units in the string. 65

7. An insulator formed of a plurality of units in a string, ball and socket joints separately connecting said units, adjacent units having oppositely extending flanges thereon overlapping each 75

other, two of said overlapping flanges, one on each unit, each being movable relative to the unit with which it is connected to permit access to the joint connecting said units.

5. 8. An insulator string formed of a plurality of units each comprising a dielectric member, and metal fittings connecting said member with adjacent units in the string, the fittings of adjacent units having a ball and socket connection with each other, the units in said string having baffles thereon, the baffles on one unit each overlapping an oppositely extending baffle on an adjacent unit and forming an enclosing housing for the joint between said units, said 15 housing being connected to the outer atmosphere by a labyrinthine passage between said baffles, one of said baffles being movable relative to the unit on which it is mounted to open said passage.
9. In combination a plurality of insulator units 20 connected together, one above another in a string, one of said units comprising a dielectric member, a cap secured to a portion of said member and disposed at the lower side of said member, a pin secured in an opening in said portion and projecting from the upper side of said member, a flange projecting upwardly from said member about said pin, a second flange projecting downwardly from said member about said cap, said second flange being of greater diameter than said 25 30 first flange and extending downwardly past the bottom of said cap and a sufficient distance to

overlap the upwardly extending flange of a like unit connected by its pin to the cap of said first named unit.

10. In combination, a plurality of insulator units connected together in a string, one above another, one of said units comprising a dielectric member, fittings for said member comprising a cap secured to a portion of said dielectric member and disposed at the lower side of said member and a pin secured in an opening in said portion and projecting from the upper side of said member, spaced concentric flanges projecting upwardly from said member about said pin and spaced concentric flanges projecting downwardly from said member about said cap, said downwardly projecting flanges being of sufficient length to extend below said cap and to overlap the upwardly projecting flanges of a like unit connected by its pin to the cap of said first named unit, so that said flanges form a labyrinthine passage connecting the space about said cap and pin with the outer atmosphere, each downwardly projecting flange being disposed outside of an upwardly projecting flange, the innermost downwardly projecting flange being of 25 greater diameter than the innermost upwardly projecting flange to conform to the diameters of the fittings which they respectively surround.
